UNITED STATES PATENT OFFICE.

LEO MORSE, OF NEW YORK, N. Y.

WHEELED FIGURE TOY.

1,223,287.

Specification of Letters Patent. Patented Apr. 17, 1917.

Application filed February 7, 1917. Serial No. 147,061.

To all whom it may concern:

Be it known that I, LEO MORSE, a citizen of the United States, and a resident of the city of New York, borough of Manhattan, 5 in the county and State of New York, have invented a new and Improved Wheeled Figure Toy, of which the following is a full, clear, and exact description.

This invention relates to figure toys and 10 has particular reference to a device of this character mounted upon wheels for rolling thereof along a table, floor or other surface.

Among the objects of the invention is to 15 construct a toy of unusually attractive appearance, the same having the property of causing the rotation of a portion thereof around a vertical axis coincidentally with the translation of the device along a horizontal surface.

20 Another object of the invention is to provide a toy, the main portion of which is adapted to maintain an upright position automatically under practically all conditions.

Another object of the invention is to produce a toy of an attractive or fantastic appearance that is adapted to maintain itself 25 erect automatically, even though supported upon two wheels only.

A still further object is to provide a toy 30 for children, the same comprising a body having a transverse axle journaled therein, supporting means for the axle and body, and gravity controlled means carried by the body to hold the body upright irrespective of the 35 movement or position of the device along the support for the wheels.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had to 45 the accompanying drawings, in which like reference characters designate the same parts in the several views, and in which—

Figure 1 is a perspective view showing 50 my improvement in one of many of the possible embodiments thereof;

Fig. 2 is a vertical longitudinal section of the same; and

Fig. 3 is a vertical transverse section.

Referring now more particularly to the 55 drawings, I show a figure toy comprising a

body 10, preferably hollow, of any desired configuration, but which may be decorated or formed in any suitable manner to represent some real or fantastic figure of an attractive nature. An axle 11 is passed horizontally through the body, preferably close below the central diameter thereof, and a pair of supporting wheels 12 are secured to the ends of the axle on opposite sides of the body. The relation, however, of the axle to 60 the central diameter of the body will depend upon the relative size of the body and the wheels, the main consideration in this particular being that the bottom portion of the body must swing above the plane of the 65 surface supporting the wheels. A gravity member, such as a weight, 13 is secured within the bottom portion of the body and serves under ordinary conditions automatically to maintain the body erect irrespective of the 70 rotation of the wheels and axle. A staple 14, or its equivalent, is connected to the front portion of the body to which a cord or the like may be connected for the purpose of drawing the device along the supporting 75 surface.

15 indicates a member carried by the body, preferably above the body where it may represent a head. This member is secured to a vertical axle 16, around the axis of which 80 the head is adapted to rotate. The axle 16 extends downwardly through a sleeve or neck member 17 fixed to the upper portion of the body. The member 15, as above indicated, may be designed or decorated to 85 represent the head of a doll or one or more animals, either of a real or fantastic nature, and while I may hereinafter refer to this part as a head, I wish it to be understood that this term is broad enough to cover any 90 device adapted to be supported for rotation around an axis upon the body at an angle to the main supporting axle 11.

Any suitable means may be provided to 95 effect the rotation of the head automatically. For this purpose I provide a pair of friction elements 18 and 19, secured respectively to the axle 11 and the inner end of the axle 16. The friction member 18 is secured not far remote from the center of the axle 11, 100 such distance being determined by the rate of rotation to be imparted to the head. The weight of the head and axle 16 is sufficient to insure the frictional driving connection 105 between the two friction members. I do not 110

wish, however, to be unnecessarily limited to friction elements for insuring the rotation of one of the axles from the other.

This device may be made entirely of celluloid, except perhaps the weight 13, or any other suitable material may be employed in its construction. It may be made strong and substantial at a low cost and in practice has proved to be exceedingly attractive 10 as well as harmless to the children who play with it.

I claim:

1. In a figure toy, the combination of a non-rotary body, supporting means for said body adapted to rotate about a horizontal axis, a head for the body, and means to automatically rotate the head around its axis

at an angle to the supporting axis while the toy is being transported.

2. In a figure toy, the combination of a hollow body, a horizontal supporting axle for the body extending therethrough, a pair of supporting wheels secured to the ends of the axle on opposite sides of the body, a weight within the body below the axle serving to hold the body from rotation and erect, a head for the body, an axle secured to the head and extending into the body, and devices carried respectively by the two axles serving to cause the rotation of the head around the axis of its axle while the toy is being transported along a supporting surface.

LEO MORSE.

Copies of this patent may be obtained for five cents each, by addressing the "Commissioner of Patents, Washington, D. C."
